(57) **CLAIM**

The ornamental design for a weighted sports racket, as shown and described.

DESCRIPTION

FIG. 1 is a front elevational view of the weighted sports racket;

FIG. 2 is an enlarged perspective view thereof;

FIG. 3 is a front elevational view of FIG. 2;

FIG. 4 is a rear elevational view of FIG. 2;

FIG. 5 is a side elevational view of FIG. 2;

FIG. 6 is a top plan view of FIG. 2; and,

FIG. 7 is a bottom plan view of FIG. 2.

The broken line showing is included for the purpose of illustrating an unclaimed sports racket and forms no part of the claimed design.

1 Claim, 6 Drawing Sheets
